UNITED STATES PATENT OFFICE

122,432

DESIGN FOR A PORTABLE SERVICE BAR

Felix Czapski (also known as Felix C. Bonnet), Chicago, Ill.

Application June 14, 1940, Serial No. 93,010

Term of patent 7 years

To all whom it may concern:

Be it known that I, Felix Czapski, also known as Felix C. Bonnet, a citizen of Germany, but an applicant for citizenship in the United States, and a resident of Chicago, county of Cook and State of Illinois, have invented a new, original, and ornamental Design for a Portable Service Bar, of which the following is a specification, reference being had to the accompanying drawing forming a part thereof, in which Fig. 1 is a perspective view of a portable service bar, showing my new design; Fig. 2 is a top plan view of the portable service bar, on a reduced scale, and Fig. 3 is a detail horizontal sectional view, on an enlarged scale, with respect to Fig. 1, through a portion of the portable service bar as taken on the line 3—3 of Fig. 1.

I claim:

The ornamental design for a portable service bar, substantially as shown.

FELIX CZAPSKI.
